JAMES M. PECKHAM, OF FALL RIVER, MASSACHUSETTS, ASSIGNOR OF ONE-HALF TO RICHARD THACKERAY, OF FALL RIVER, MASSACHUSETTS.

WARP-LET-OFF MECHANISM FOR LOOMS.

SPECIFICATION forming part of Letters Patent No. 728,001, dated May 12, 1903.

Application filed August 23, 1902. Serial No. 120,835. (No model.)

To all whom it may concern:

Be it known that I, JAMES M. PECKHAM, a citizen of the United States, residing at Fall River, in the county of Bristol and State of Massachusetts, have invented a new and useful Improvement in Warp-Let-Off Mechanism for Looms, of which the following is a specification.

In a loom the warp wound on a warp-beam is let off and held under the required tension. At the opening of the warp-shed for the passage of the shuttle to lay the weft the warp is sprung above and below the normal plane of the warp. Extra strain is suddenly exerted on the warp on the opening of each shed, and this strain is released at the closing of each shed, at which the warp returns to the normal plane. In the usual positive let-off motions the warp-threads are subjected to considerable strain, and the warp-threads are liable to stretch and produce imperfect cloth. In friction let-off motions the friction-brakes are usually weighted by placing weights on the brake-straps or by adjustably securing weights to levers connected with the friction-brakes. The securing or adjusting of these weights, which are usually detached parts, requires time and considerable experience.

The object of this invention is to construct a cheap and simple let-off mechanism which has no disconnected parts and which permits the warp-beam to rock on its bearings, so as to yield to the extra strain in forming the shed and automatically recovers the slack caused by the closing of the shed.

To this end the invention consists in the peculiar and novel construction of the brake-strap and the adjustable spring tension, as will be more fully set forth hereinafter.

Figure 1 is a rear elevation of part of a loom, showing the warp-beam and my improved let-off mechanism. Fig. 2 is a transverse sectional view of the let-off motion, on an enlarged scale, indicating in broken lines the position of the mechanism when the slack in the warp is taken up. Fig. 3 is a sectional view of the device for adjusting the spring tension on the brake, and Fig. 4 is a sectional view of the spring clamping device.

In the drawings, α indicate the end frames

of the loom; α' , the back strut connecting the end frames; α^2 , the warp-beam; $\alpha^3 \alpha^3$, the flanges on the same; $\alpha^4 \alpha^4$, the friction disks or wheels, and α^5 the shaft supporting the warp-beam.

In constructing the friction-brake I preferably take a bale-strap, such as is used on cotton-bales and always convenient to hand in a cotton-mill. These bale-straps have usually on one end a metal loop like the loop b' , secured by bending back the end of the strap b and securing the lap by a rivet. I cut the strap b to the required length, bend back the end, insert the loop b^2 , and fasten the lap by a rivet. To the strap b the friction-pads $c c$ are secured by the bolts $c' c'$. To the loop b' one end of the strap d is secured. The strap is passed through the loop b^2 . The strap is provided with a series of holes d' . The end is passed through the eyebolt d^2 and adjustably secured by the belt-hook d^3 to the strap, as is clearly shown in Fig. 2. The eyebolt is provided with the two nuts $d^4 d^4$ and is adjustably secured to the spring-plate e , which is secured near the opposite end in the bracket e' by the clamp-screw e^2 , the bracket being secured to the back strut α' by the bolt e^3 .

The tension of the spring-plate e is adjusted by the four-sided block e^4 , provided with the handle e^5 . The block is secured to the back strut by the bolt e^6 , on which it may be turned, so as to bring either one of the four sides of the block to bear on the spring-plate, the four sides being each at a different distance from the center of the bolt e^6 , on which the block e^4 turns. The spring tension of the spring-plate may be adjusted by turning the block e^4 .

When my improved warp-let-off mechanism is in use on a loom, the spring-plate e draws the strap b and the friction-pads $c c$ against the peripheral surface of the friction-disk α^4 and restrains the let-off of the warp. The strain of the warp on the warp-beam is resisted by the friction-strap. The opening of the warp-shed causes the warp-beam to partly turn in the direction of the arrow f and places the let-off mechanism into the position shown in solid lines in Fig. 2, while in closing the shed the spring-plate e acts to take up the slack by partially turning the warp- 100

beam in the reverse direction (indicated by the arrow f') and places the straps into the position indicated in broken lines in Fig. 2. By this construction and arrangement the 5 strain on the warp delivered from the warp-beam is maintained uniform, because the spring-plate e when properly adjusted acts promptly at each formation of a warp-shed, and the arrangement of the straps permits the 10 rocking of the warp-beam.

Having thus described my invention, I claim as new and desire to secure by Letters Patent—

1. In a warp-let-off mechanism, the combination with the warp-beam and the friction-disk connected with the same, of a friction-strap inclosing the friction-disk, friction-pads on the same, loops on the ends of the friction-strap, a spring-plate, and a strap, connected 15 with one end of the friction-strap, extending through the loop on the other end of the friction-strap and connected with the spring, as described.

2. In a warp-let-off mechanism, the combination with the warp-beam, the friction-disk connected with the same, a friction-strap, friction-pads on the strap and loops on the 20 ends of the friction-strap, of a spring-plate, a rotatable block eccentrically mounted having a multiple of faces, and connection between the spring-plate and the friction-strap, 25

whereby the strain on the friction-strap may be regulated, as described.

3. In a warp-let-off mechanism, the combination with the friction-brake, of the bracket 35 e' secured to the loom-frame and provided with the clamp-screw e^2 , the spring-plate e secured in the bracket e' by the clamp-screw e^3 , the block e^4 rotatably secured to the loom-frame above the spring e the several faces of 40 said block being at different distances from the pivotal point, the eyebolt secured to the spring e by the nuts d^4 and connection between the eyebolt and the friction-brake, as described. 45

4. In a let-off mechanism for looms, the combination with the warp-beam and the friction-disk on the same, of the friction-strap b , the loops b' and b^2 on the ends of the same, the strap d , the eyebolt d^3 adjustably secured 50 to the spring-plate e , the spring-plate e , the rear strut a' , the bracket e' on the same, and the rotatable multifaced block e^4 , whereby the strain on the friction-brake may be adjusted, as described. 55

In testimony whereof I have signed my name to this specification in the presence of two subscribing witnesses.

JAMES M. PECKHAM.
